UNITED STATES PATENT OFFICE.

WILLIAM BROWN, OF NEW YORK, N. Y.

FLYING MACHINE.

Application filed April 12, 1924. Serial No. 706,195.

To all whom it may concern:

Be it known that I, WILLIAM BROWN, citizen of the United States, residing at New York city, in the county of New York and State of New York, have invented certain new and useful Improvements in Flying Machines, of which the following is a specification.

This invention relates to flying machines, having more particular reference to a flying machine of the helicopter class, in which a rotary element of the turbine type exerts both a downward suction of air to cause the machine to rise, and a direct lifting action on suitably placed members, the invention having for a general object the provision of a novel flying machine of this type. The present invention is a further development of a previous one disclosed in a prior application for patent filed Oct. 6, 1923, under Ser. No. 666,888.

For further comprehension of the invention, and of the objects and advantages thereof, reference will be had to the following description and accompanying drawings, and to the appended claims in which the various novel features of the invention are more particularly set forth.

Fig. 1 of the drawings is a fragmentary horizontal sectional view of my improved flying machine, this view being taken on the line 1—1 of Fig. 2.

Fig. 2 is a transverse vertical sectional view thereof, taken on the line 2—2 of Fig. 1 the rotary element being shown in a different position than in Fig. 1.

Fig. 3 is a detail horizontal sectional view of the automatic valve control element.

Fig. 4 is a fragmentary vertical sectional view, taken at the point indicated by line 4—4 on Fig. 1 and showing the control elements for the annular explosion chambers.

Fig. 5 is a fragmentary detail view showing the means for operating the exhaust valves of the explosion chambers.

Fig. 6 is a side view of the complete machine.

Fig. 7 is a plan view showing the control means for the propulsion and steering device.

Fig. 8 is a detail vertical sectional view of one of the valve control devices.

Fig. 9 is a plan view thereof.

Fig. 10 is a plan view of the whole machine.

As here embodied my improved flying

machine comprises a large disklike member 10 which is of hollow construction and horizontally disposed. Fixed at opposite ends to this member are the front and rear cabins 11 and 12, the former of which is the pilot's cabin while the other may be used for any desired purpose. Extending between these cabins, above the disk member 10, are two wall elements 13 which enclose two longitudinally separated spaces for the passengers. The machine is mounted on suitable wheels 14.

Extending between the two walls 13 are the partitions 13' which separate the front and rear passenger spaces and form the end walls of a well 16 through which air is drawn downward to sustain the machine by the downward suction. Located in this well 16 is a valve which controls the passage of air therethrough. This valve comprises a pair of aprons 18 each made up of a number of rigid strips fixed on a flexible backing element. Connected to opposite ends of these aprons are the opposite ends of the cords 19 whereby the aprons are moved toward or away from one another to vary the extent or area of the opening through which the air is drawn. These aprons are guided in the guide members 20 which are projected laterally beyond the walls 13 and extending partly along the bottom of the well, the cords 19 passing around suitable pulleys 19'. These cords pass between their ends around a large drum 21 mounted in the well 16 and to which is co-axially fixed a smaller drum or pulley 21' around which is looped a cord or cable 22 which passes around a suitable guide pulley 23 and is looped over another pulley 24 provided with a crank handle 25, this pulley being located near the operator's seat 11' in the cabin 11. Looped over the guide pulley 23 is a second cord 26 which is looped also over a pulley nut 27 through which is threaded a screw 27' connected to an arm 28 on a flap valve 28' in an exhaust conduit 29 leading rearwardly from the member 10. This exhaust conduit may terminate at its rear end in an enlarged chamber 29' from which a number of exhaust bell-like exhaust members 29" lead. The discharge of the exhaust on these members acts to propel the machine.

Carried within the member 10 are a pair of rotary elements located one above the other whose rotation induces suction

through the well 16. The lower element comprises a pair of annular explosion chambers 30 which are fixed to the outer ends of a number of air compressors 31 having a general spoke-like arrangement with respect to the said chambers and rigidly united by a common frame element 31'. Extending outwardly from these explosion chambers are pipes or conduits 32 which have their outer ends in the form of nozzles 32' through which gases under pressure are delivered at an oblique angle on vanes 33 carried by the upper rotary member as will be presently set forth. The conduits curving rearwardly and outwardly from the chambers 30. Air under pressure, and gasoline, are introduced into the explosion chambers, which latter are here shown as of circular cross section, and the mixture is then ignited as usual by an electric spark, water in small quantities being introduced into the explosion chambers after the explosion has taken place, the water increasing the efficiency of the gases by the generation of steam and also preventing overheating of the explosion chambers. The compressed air is delivered to the explosion chambers through pipes 48 suitably branched as at 50 to each chamber.

The air compressors 31 each comprise tandem cylinders separated by the heads 41 and in which are pistons 42 connected by the rods 43 with an eccentrically disposed wrist pin element 44 formed on a rigid post 45 extending concentric of the member 10. The air is conducted to the cylinders through branched pipes 46 in which are suitable checkvalves 47 and is discharged therefrom through the pipes 48 to which lead branches 48' having checkvalves 49 therein. From each of these pipes (see Fig. 4) branches 50, in which are checkvalves 51, lead to the respective explosion chambers 30, the air being adapted to be admitted in alternation to each chamber. The admission of air is controlled by a sleeve valve 52 in the pipe having an opening 53 in the side thereof adapted to alternately register with the branches 50. The sleeve valve is adapted to receive longitudinal reciprocatory motion from a rod 54 connected thereto at one end and having at its opposite end a pivoted section 54' provided with a head 55 adapted to be engaged in spiral grooves 56 in adjacent faces of a pair of fixed disks 57 located concentrically with the chambers 30 and fixed to the post 45, the grooves in the two disks being respectively right and left hand. Projecting upward rigidly from the rod section 54' is a finger 58 which is adapted to engage the annular shoulders 59 to throw the said section upward and downward to engage the head 55 with the respective spiral grooves 56. The grooves in the two disks may vary in depth from the end to end

thereof so as to cause the heads 55, as they travel along the groove in one disk, to be gradually moved toward the other disk to facilitate transfer of the head from one groove to the other. The rod section 54' 70 may have sufficient frictional engagement with the main rod length to be held in the operative position to which it is adjusted. As the rotary element moves, the sleeve valves 52 will be caused to reciprocate. To 75 start the machine, a number of compressed air tanks 60 are provided from which suitably branched pipes 60' lead to the respective explosion chambers. These pipes 60' have valves 61 thereon whose handles 61' 80 are operated in a manner to be presently set forth. Pipes 60' may lead from the air compressors to the tanks 60.

The pipes 32 are suitably branched as at 85 32'' to connect to the explosion chambers 30 and on these branches are rotary valves 62 whose spindles 63 (see Fig. 5) have fixed thereon the gears 63' engaged with the rack element 65 formed on one arm of a U-bar 66 fixed to the sleeve 52. The exploding of the charges in the chambers 30 is done by approaching the contact elements 67 carried by the rods 54 with other fixed contact elements 68 which are wired to spark plugs of ordinary construction in the respective chambers. The lower rotating element carries a number of outwardly and rearwardly projecting arms 69 which extend substantially one-half the full depth of the chamber in the member 10, their lower edges being closely adjacent the bottom wall of said chamber. As will be understood, a vacuum will be created behind each arm as it revolves, and the air is drawn downward through the well 16, and passes out through openings in the periphery of the member 10. As here shown the top and bottom walls of said member 10 are connected by the posts 70, the spaces between these posts providing the said air discharge openings. Projecting outwardly and downwardly from the top edges of these openings at the sides of the machine are the baffle plates 71, while the openings under these baffle plates are adapted to be controlled by the hinged shutters 72 which have the arms 73 fixed to their hinge pintles, these arms having connected thereto the cords 74 which pass over suitable guide pulleys and are looped around a small drum 75 fixed coaxially to the drums 21 and 21'. By adjusting these shutters the machine may be caused to climb, hover, or descend as may be desired.

The upper rotary element comprises a series of arms 76 radiating from a hub 76' 125 freely surrounding the post 45, said arms being of a depth to substantially close the space between the lower rotary element and the top of the member 10. Fixed to the undersides of these arms 76 are the depend-

ing members 77 to the lower ends of which is fixed the channeled annular member 78 whose inner face is formed with the vanes 33.

5 To steer and propel my improved flying machine I provide a pair of rotary cylinders 82 which control the mouths of conduits 16' leading laterally from the well 16, these cylinders having formed in the sides there-
 10 of the openings 83. In these cylinders are pistons 86 fixed on rods 87 on which the cylinders are also mounted to swing, the cylinders having an ordinary feather connection with the rods so as to permit the latter to move longitudinally independently of the cylinders while rotary movement of the rod swings the cylinders. Control of these parts is effected by the steering element illustrated in detail in Fig. 7 and
 20 which is mounted in the cabin 11. This steering element comprises an outer hollow shaft 90 and an inner solid shaft 91 suitably supported in a frame element 92 and having handwheels 90' and 91' on their
 25 respective ends. Fixed to the hollow shaft 90 is a mutilated bevel gear 93 which is adapted to be brought selectively into engagement with either one of a pair of bevel pinions 94 mounted on transverse shafts 95, these shafts having other bevel pinions such as 96 thereon which mesh with like pinions such as 97 having a non-rotative but sliding engagement with the rods 87. Upon the solid shaft 91 are fixed the sprocket wheels 98 over which are looped the chains 99 engaging also over like sprocket wheels such as 100 having threaded bores through which pass the threaded ends of rods 87.

By adjusting the cylinders 82 the area
 40 of the openings into the conduits 16' may be varied independently in each, while by adjusting the pistons 86 backward or forward the direction of flow of the air inward through the conduits may be caused
 45 to be either backward or forward, causing the machine to be propelled in a forward or backward direction, steering of the machine being effected by individually adjusting the cylinders 82.

50 The gasoline is contained in a tank 110 located near the rear of the machine and flows by gravity through a suitable pipe, through a passage 111 in the post 45 and into a semi-cylindrical chamber 112 partially surrounding the post 45 but fixed to the lower rotary element, the flow of gasoline only taking place at the time the ports in the post and the chamber wall are in registry. The gasoline is fed from this chamber to tanks 113 supported by the rotary element by means of a pump 114 which is operated by a crank shaft 115 rotated by means of meshing gears 116 and 117 fixed respectively to the said shaft and the post 21. A similar arrangement, com-

prising a chamber 118 connected to a supply tank 119, and a pump 119' is provided to introduce small quantities of water into the explosion chambers at the time of the explosion. The gasoline is delivered from the tanks to the explosion chambers through pipes 120 having valves 121 thereon which are controlled by means operated by the sleeves 52 as above shown in Fig. 4. These pipes 120 have other valves 122 thereon 73 for hand control, these valves having handles 122'.

Formed on the cylindrical wall of the member 10 is a curved baffle member or flange 125 and from the space below said flange pipes 126 lead to the centre of the machine and conduct the air which is thrown by the arms 69 into said space inward to enter the pipes 46. These pipes 126 lead upward at their inner ends into a horizontal partition member 127 in which are flap valves 128.

These valves 128, as well as the valves 61 and 122 are operated individually by the means shown in Figs. 8 and 9. A number of pairs of curved arms 135 have attached thereto ropes 136 which lead to the valve handles. Connected to these arms are fingers 137 which are attached to opposite reaches of ropes 138 leading around pulleys 139. These ropes connect, for the flap valves 128, to a foot lever 140, and for the other valves to hand levers such as 141 which may be set in position with the valves either open or closed.

As will be apparent, the arrangement of control means for the air above set forth permits the full power of the engine to be utilized for lifting or for propulsion.

This machine may be provided with a number of parachutes suitably located thereon, and which may be opened in the event of accident.

Having thus described my invention what I claim as new and desire to protect by Letters Patent of the United States is as follow:

1. In a flying machine, a hollow disk-like member, a pair of rotatable elements therein located one above the other, said member being formed with an intake opening in the top thereof adjacent the centre thereof, and outlet openings at the periphery thereof, vanes carried by said upper rotatable element, and means carried by said lower rotatable element for discharging a fluid upon said vanes to cause said rotatable elements to rotate and exert a suction downward through said intake opening.

2. In a flying machine, a hollow disk-like member, a pair of rotatable elements therein located one above the other, said member being formed with an intake opening in the top thereof adjacent the centre thereof, and outlet openings at the periphery thereof,

vanes carried by said upper rotatable element, and means carried by said lower rotary element for discharging a fluid upon said vanes to cause said rotary elements to rotate and exert a suction downward through said intake opening, and lifting elements adjacent the sides of the machine against which the air is directed.

3. In a flying machine, a hollow disk-like member, a pair of rotatable elements therein located one above the other, said member being formed with an intake opening in the top thereof adjacent the centre thereof, and outlet openings at the periphery thereof, vanes carried by said upper rotatable element, and means carried by said lower rotary element for discharging a fluid upon said vanes to cause said rotary elements to rotate and exert a suction downward through said intake opening, and a valve controlling said intake opening, said valve comprising a pair of plates movable toward and away from one another.

4. In a flying machine, a hollow disk-like member, a pair of rotatable elements therein located one above the other, said member being formed with an intake opening in the top thereof adjacent the centre thereof, and outlet openings at the periphery thereof, vanes carried by said upper rotatable element, and means carried by said lower rotary element for discharging a fluid upon said vanes to cause said rotary elements to rotate and exert a suction downward through said intake opening, and lifting elements adjacent the sides of the machine against which the air is directed, each of said rotary elements comprising a number of arms projecting outwardly and backwardly and being of a depth substantially one-half the depth of the said disk-like member.

5. In a flying machine, a hollow disk-like member, a pair of rotatable elements therein located one above the other, said member being formed with an intake opening in the top thereof adjacent the centre thereof, and outlet openings at the periphery thereof, vanes carried by said upper rotatable element, and means carried by said lower rotary element for discharging a fluid upon said vanes to cause said rotary elements to rotate and exert a suction downward through said intake opening, and shutters controlling the said peripheral openings.

6. In a flying machine, a hollow disk-like member, a pair of rotatable elements therein located one above the other, said member being formed with an intake opening in the top thereof adjacent the centre thereof, and outlet openings at the periphery thereof, vanes carried by said upper rotatable element, and means carried by said lower rotary element for discharging a fluid upon said vanes to cause said rotary elements to

rotate and exert a suction downward through said intake opening, and lifting plates extending downwardly and outwardly from the edges of the said peripheral openings.

7. In a flying machine, a hollow disk-like member, a pair of rotatable elements therein located one above the other, said member being formed with an intake opening in the top thereof adjacent the centre thereof, and outlet openings at the periphery thereof, vanes carried by said upper rotatable element, and means carried by said lower rotary element for discharging a fluid upon said vanes to cause said rotary elements to rotate and exert a suction downward through said intake opening, and lifting plates extending downwardly and outwardly from the edges of the said peripheral openings, and shutters for controlling the said openings.

8. In a flying machine, a rotary element, a hollow disk-like member in which said rotary element is mounted, a second rotatable element mounted in said member above and co-axially with said rotary element, a series of air compressors radiating from the centre of said rotary element and adapted to be operated by rotation thereof, a pair of annular explosion chambers on said rotary element, vanes carried by said second rotatable element, conduits leading from the said explosion chambers to points adjacent said vanes, and means for delivering the gas from the respective explosion chambers alternately to said conduits.

9. In a flying machine, a rotary element, a hollow disk-like member in which said rotary element is mounted, a second rotatable element mounted in said member above and co-axially with said rotary element, a series of air compressors radiating from the centre of said rotary element and adapted to be operated by rotation thereof, a pair of annular explosion chambers on said rotary element, vanes carried by said second rotatable element, conduits leading from the said explosion chambers to points adjacent said vanes, and means for delivering the gas from the respective explosion chambers alternately to said conduits, including branches from the respective chambers to each conduit, valves on said branches, gear pinions mounted on the valve stems, and a rack-bar adapted to operate said pinions.

10. In a flying machine, a rotary element, a hollow disk-like member in which said rotary element is mounted, a second rotatable element mounted in said member above and co-axially with said rotary element, a series of air compressors radiating from the centre of said rotary element and adapted to be operated by rotation thereof, a pair of annular explosion chambers on said rotary element, vanes carried by said second rota-

table element, conduits leading from the said explosion chambers to points adjacent said vanes, and means for delivering the gas from the respective explosion chambers alternately to said conduits and a ring depending from said second rotatable element on which said vanes are mounted.

11. In a flying machine, a hollow disk-like member, a pair of rotatable elements therein located one above the other, said member being formed with an intake opening in the top thereof adjacent the centre thereof, and outlet openings at the periphery thereof, vanes carried by said upper

rotatable element, and means carried by said lower rotary element for discharging a fluid upon said vanes to cause said rotary elements to rotate and exert a suction downward through said intake openings, a conduit leading rearwardly from said rotary element, and vanes mounted on the rear end of said conduit adapted to have the air jet from the conduit impinge thereon to propel the machine.

In testimony whereof I have affixed my signature.

WILLIAM BROWN.
